ELECTRIC SOLDERING IRON

Alvis R. Knowles, Manhattan Beach, Calif., assignor to
Eldon Industries, Inc., Hawthorne, Calif., a corporation
of California

Filed May 16, 1961, Ser. No. 65,198

Term of patent 14 years

(Cl. D26—1)

FIGURE 1 is a perspective view of an electric soldering iron showing my new design;

FIGURE 2 is a side elevational view;

FIGURE 3 is a front elevational view; and

FIGURE 4 is a rear elevational view thereof.

The dominant features of my design reside in the portions shown in full lines.

I claim:

The ornamental design for an electric soldering iron, as shown and described.
